Philip S. McLean, ATTORNEY

UNITED STATES PATENT OFFICE.

EDWARD KALWEIT, OF BROOKLYN, NEW YORK, ASSIGNOR TO BELOVE WATCH CASE CO., OF NEW YORK, N. Y., A CORPORATION OF NEW YORK.

WATCHCASE.

Application filed February 8, 1924. Serial No. 691,343.

To all whom it may concern:

Be it known that I, EDWARD KALWEIT, a citizen of Russia, and a resident of Brooklyn, Kings County, and State of New York, have invented certain new and useful Improvements in Watchcases, of which the following is a specification.

This invention relates to wrist watches and the objects of the invention are to provide an improved strap loop construction for watches of this type which will be more secure and at the same time less expensive than the constructions now in use and which, furthermore, will present a better appearance.

The foregoing and other objects are attained through certain novel features of construction, combination and relation of parts as set forth in the following specification.

In the accompanying drawing illustrating a practical embodiment of the invention:

Figure 1 is a plan view showing one of the loop forming staples as it is held in the shoulder-forming dies.

Figure 2 is a cross sectional view as on substantially the plane of line 2—2 of Figure 1, showing the case engaged over the projecting ends of the loop and the riveting plunger ready to "upset" the ends of the loop at the inside of the case.

Figure 3 is an inside view of the completed case with the strap loops permanently secured in place.

Figure 4 is an enlarged broken sectional view of the joint between the loop and case.

The watch case or shell 5 is shown as of typical construction, having opposite flat sides 6 for the attachment of the strap loops 7.

These strap loops are usually made of wire bent to staple form and prior to this invention have been secured in place by soldering the ends of the same to the outer surface of the case. These soldered joints vary both in strength and appearance and because of the small areas of contact between the ends of the loop and the case, provide at best a rather insecure form of joint. These soldering operations, also, are relatively expensive and require skilled labor.

In the present invention the ends of the strap loops are passed through opening 8 in the flat sides of the case and headed at the

inside of the case, as indicated at 9. As a preliminary to this heading over operation, shoulders are formed on the loops for engagement with the outside of the casing so that in the final relation of the parts the loops will be secured rigidly at the outside as well as at the inside of the casing.

These shoulders are shown in the form of fins or webs 10 projecting from opposite sides of the shank portions 11 of the loops and a convenient and practical method of providing the same is illustrated in Figures 1 and 2, where 12 and 13 designate companion die members for squeezing out these fins. These dies have cooperating recesses 14 to receive the shank portions of the loops, forming cavities slightly smaller than the diameter of the shanks so that when the loops are positioned between the dies and the dies brought together, the shanks will be reduced in diameter at 15 and the excess of metal thus provided be squeezed out at the sides in the form of the tapered fins.

The gripping effort of the dies is utilized to hold the loop in position for engaging the watch case thereover and while the heading over operation is being performed. As shown in Figure 2 the dies grip the loop so that the ends of the same project far enough for the casing to be slipped over the same and when the two parts are thus assembled, a plunger 16 descends and flattens the loop ends over into engagement with the inner surface of the shell. In this way the three operations of shouldering the loop, assembling the case and loop and finally heading over the ends of the loop at the inside of the case are all performed in the one mechanism and in a series of quickly succeeding steps. Furthermore, these operations are quite simple and may be accomplished without the exercise of any special skill.

The invention, it will be seen, provides a permanent and rigid joining of the strap loops to the watch case and the structure has the further advantage of providing a much neater and stronger connection than can be effected by soldering. Preferably, in the riveting operation considerable pressure is applied, sufficient to flatten the heads down into the metal of the case, in the manner indicated in Figure 4, so as to leave the inside surface of the case smooth and free of any obstructions. The heavy pressure employed

also has a tendency to force the case down over the shoulders or fins 10. The result of these effects is to make the loop practically an integral part of the case.

5. What is claimed is:

1. In combination, a watch case having openings in the side of the same and a strap loop having its ends passed through said openings and flattened down into holding engagement with the inside of the case, said loop further having integral enlargements providing shoulders engaging the outside of the case and said shoulders and said flattened ends respectively being forced into the outer and into the inner surface of the case, whereby said loop is braced and rigidly held by integral portions both inside and outside the case and which are embedded in the material of the case.
- 10 2. In combination with a watch case having an opening in one side, a strap loop having integral fins pinched out at the sides of the same limiting the extent of entry into the opening in the case and the end of the loop being headed over inside the case to rigidly and permanently secure said loop in place.
- 15 3. The process of attaching a strap loop to a watch case which comprises squeezing an integral enlargement in the shank portion of the loop, engaging a watch case shell over the projecting end of said shank while the same is held by the squeezing mechanism, flattening over the end of the shank inside the shell while the loop is still held by the same mechanism and forcing said flattened end down into the material inside the case, displacing such material beneath the flattened portion sufficiently to receive the same sub-

stantially flush with the inner surface of the case.

4. The process of attaching strap loops to watch cases which comprises squeezing integral enlargements in the shank portions of a strap loop, engaging a watch case shell over the projecting ends of the loop while the same is held by the squeezing mechanism and then flattening over the ends at the inside of the shell while the loop is still held by the same mechanism.

5. In a structure of the character disclosed, a watch case or the like and a strap loop having an integral shoulder at the outer face of the case and a head inside the case, said head being flattened down into the wall of the case and the material of the wall beneath said head being displaced laterally by the head to thereby provide a self-conforming seat for the head and form a rigid permanent joint substantially flush and smooth at the inner surface of the case.

6. In a structure of the character disclosed, a watch case or the like and a strap loop having an integral shoulder at the outer face of the case and a head inside the case, said head being flattened down into the wall of the case and the material of the wall beneath said head being displaced laterally by the head to thereby provide a self-conforming seat for the head and form a rigid permanent joint substantially flush and smooth at the inner surface of the case, the material at the outer surface of the wall being similarly displaced by the shoulder thereat to provide a self-conforming seat therefor.

In witness whereof, I have hereunto set my hand this 6th day of February, 1924.

EDWARD KALWEIT.
